UNITED STATES PATENT OFFICE.

THOMAS C. WOODWARD, OF NEW YORK, N. Y., ASSIGNOR TO ELIAS A. WILKINSON, TRUSTEE, OF NEWARK, NEW JERSEY.

SEWING-MACHINE.

SPECIFICATION forming part of Letters Patent No. 268,763, dated December 5, 1882.

Application filed September 8, 1882. (No model.)

To all whom it may concern:

Be it known that I, THOMAS C. WOODWARD, of New York city, New York, have invented certain, new, useful, and important Improvements in Sewing-Machines, described in this specification and the drawings thereof.

Figures 1 and 2 are perspective views of one form of the improvements. Fig. 3 is a top view of a portion thereof. Fig. 4 is a front view of a portion of a sewing-machine embracing the same.

The invention consists in improvements relating to the driving-wheel or belt-wheel, whereby the belt can be put on or off the same by turning it with the treadle or otherwise in an automatic manner.

In the form of construction shown the belt-wheel or driving-wheel A has a continuous oblique belt groove or track, B, and a straight switch groove or track, C, leading therefrom at D and terminating at E, the opposite part of the belt-wheel between these two points, that would be embraced by a continuation of the switch-groove, being cut away, as shown, 25 forming an offset, F.

To illustrate the operation of the belt-wheel, it is shown on a journal, G, connected by a belt, H, in the oblique belt-groove to a belt-pulley, K, on a journal, L, the journals being 30 fastened in a support, M, having a belt-guard, N, with a belt-groove, O, opposite to the switch-groove. The belt-wheel is shown with the belt in position, and adapted to be turned by the crank P from right to left, in the direction indicated by the arrow, to keep the belt on in the oblique belt-groove, and to turn backward or in the opposite direction, to run the belt into the switch-groove and off. When the belt is run off the switch-groove it has a slack, R, 35 in the offset, and drops into the belt-groove in the belt-guard, which permits the continued backward motion of the belt-wheel. By having no belt-groove in the belt-guard the backward motion of the belt-wheel will be arrested by the clamping of the belt between the two. When the belt is off, by turning the belt-wheel in the forward direction the belt will take the 40 switch-groove and run on, and when it is on, by turning the belt-wheel in the backward direction it will take the switch-groove and run off.

The belt-wheel is peculiarly adapted to sew-

ing-machines, in which it is frequently necessary to slacken the belt on the belt-pulley on the driving-shaft L, to turn the head of the machine sidewise, to fix or oil the under works. To accomplish this the belt can be run off the driving-wheel and slackened by a backward motion of the treadle Y, and when the head of the machine is in position again the belt 60 can be run on again by a forward motion of the treadle, thus avoiding the unpleasant operation of removing or replacing the belt by hand, or both, or of applying a belt-shifter by hand for the purpose.

The details of construction and operation may be varied within the scope of the improvements. For example, the belt-wheel or driving-wheel may be made in skeleton form, with any kind of a belt-track and switch-track; the 70 form and application of the belt-guard may be modified, and the belt-wheel may be used for other purposes than that referred to herein.

I claim as my invention—

1. The combination, in sewing mechanism, 75 of driving-wheel A, having belt-groove B and switch-groove C, belt-guard N, having belt-groove O, belt H, treadle Y, and driving-shaft L, having belt-pulley K, substantially as set forth.

2. The combination, in sewing mechanism, 80 of a driving-wheel having an oblique belt-groove and a straight switch-groove therefrom, a belt-guard around the lower portion of the same, and having a belt-groove opposite 85 the switch-groove, and a belt from the driving-wheel to a belt-pulley on the driving-shaft, substantially as set forth.

3. The combination, in sewing mechanism, 90 of a driving-wheel having a belt-track and a switch-track therefrom, a belt-guard to keep the belt in proper relation to the tracks, and a belt from the driving-wheel to a belt-pulley on the driving-shaft, substantially as set forth.

4. The combination, in a sewing-machine, 95 of a driving-wheel having an oblique belt-track and a straight switch-track therefrom, and supporting and operating mechanism, substantially as set forth.

5. The combination, in a sewing-machine, 100 of a driving-wheel having a belt-track and a switch-track therefrom, and supporting and operating mechanism, substantially as set forth.

6. The combination of a belt-wheel having an oblique belt-track and a straight switch-track therefrom, with a belt-guard around the lower portion of the same, and having a belt-groove opposite the switch-track to keep the belt in proper relation to the belt-wheel, a belt-pulley, and supporting and operating mechanism, substantially as set forth.

7. The combination of a belt-wheel having a belt-track and a switch-track therefrom, a belt-guard to keep the belt in proper relation to the track, and supporting and operating a mechanism, substantially as set forth.

8. A driving-wheel having a continuous oblique belt-track and a segmental straight switch-track therefrom, substantially as set forth.

9. A belt-wheel having a belt-track and a

switch-track from the belt-track, substantially as set forth.

10. A belt-wheel having a switch-track to throw a belt on when the wheel is turned in one direction, and to throw the belt off when the wheel is turned in the opposite direction, substantially as set forth.

11. A belt-wheel adapted to throw a belt on and retain it when the wheel is rotated in one direction, and to throw the belt off when the wheel is rotated in the opposite direction, substantially as set forth.

In witness whereof I hereunto subscribe my signature in presence of two witnesses.

THOMAS C. WOODWARD.
